UNITED STATES PATENT OFFICE.

JACOB S. VANDENBERGH, OF CANANDAIGUA, NEW YORK.

COMPOUND FOR DESTROYING CARPET BUGS AND WORMS.

SPECIFICATION forming part of Letters Patent No. 256,414, dated April 11, 1882.

Application filed September 10, 1881. (No specimens.)

To all whom it may concern:

Be it known that I, JACOB S. VANDENBERGH, of Canandaigua, in the county of Ontario and State of New York, have invented a new and Improved Compound for Destroying Carpet Bugs and Worms, of which the following is a specification.

My composition consists of the following ingredients combined in the proportions stated: 10 tobacco extract, six ounces; potash mixture, one ounce; spirits of turpentine, one ounce.

First. To make the tobacco extract, one and a half pound of tobacco is boiled in six quarts of water for about one hour, upon which the liquor is strained. One quart of alcohol is then 15 poured on the tobacco, and is then mixed with the liquid previously drawn off, and then strained. This mixture of watery extract of tobacco and the alcoholic extract forms the 20 above-mentioned extract of tobacco.

Second. To make the potash mixture, sixteen ounces of potassium oxide, one ounce of muriate of ammonia, and one ounce of salts of tartar are dissolved in one gallon of soft water 25 and allowed to stand over night.

To make eight ounces of the compound I mix six ounces of tobacco extract and one ounce each of turpentine and potash mixture.

The compound is used in the following manner: It must be shaken thoroughly before being applied. It is applied with a coarse feather, &c., on the under side of the carpet for three or four inches from the edge. A rag saturated with the compound is to be placed in drawers, boxes, &c. The mixture is to be applied once 30 a week as long as eggs of the bugs appear in the carpet, drawers, or boxes.

Having thus fully described my invention, I claim as new and desire to secure by Letters Patent—

40 The herein-described composition of matter to be used to destroy carpet bugs and worms, consisting of extract of tobacco, potassium oxide, muriate of ammonia, salts of tartar, and turpentine, in the proportions stated.

JACOB SHULTERS VANDENBERGH.
